BOWLING GAME

Clarence D. Curtis and Don P. Grafflin,
Hattiesburg, Miss.

Application October 11, 1943, Serial No. 505,742

5 Claims. (Cl. 273—39)

1

This invention relates to game devices.

It is the principal object of the invention to provide a bowling game which is simple, easy and inexpensive to construct, which is so arranged that the bowling pins are located adjacent the starting position to be accessible for setting up by the player himself, and which affords ample opportunity for the development of individual skill so that it prolongs and retains the interest of the player.

It is also an object to provide such a game in which the ball is directed in free travel toward a deflecting and turning guide which is provided with a movable part that is variably deflected by the force of the ball so that the direction of return of the ball toward the pins may be controlled by the degree of force with which the ball is initially thrown.

Other objects and advantages will be apparent from the following description, the accompanying drawing and the appended claims.

In the drawing:

Fig. 1 is a plan view of the game device constructed in accordance with the present invention;

Fig. 2 is a longitudinal view substantially on the line 2—2 of Fig. 1;

Fig. 3 is a cross sectional view on the line 3—3 of Fig. 1;

Fig. 4 is a broken cross sectional view on a larger scale looking toward the guide construction at the remote end of the alley;

Fig. 5 is a broken plan view with the top cover removed and also showing the construction of the fixed and movable portions of the guide;

Fig. 6 is a detailed plan view of the fixed guide element; and

Fig. 7 is a detailed plan view of the movable guide element.

Referring to the drawing which discloses a preferred embodiment of the invention, the device comprises a main frame 10 to which are pivotally secured the legs 11 so that upon folding the legs inwardly the entire structure may be collapsed to a flat position for ready transport and packing. When set up the legs engage against fixed stops 12 to thereby provide a firm and substantial support for the device.

The floor of the alleys is provided by wood pieces 15 which may be suitably made up of pine flooring of convenient size, and above which there is positioned a layer of linoleum felt 16, serving as a support for a bottom sheet 17 of compressed wood such as Masonite or the like, such material being preferred because of its smooth surface

2

characteristics, its resistance to wear and because it is little affected by moisture.

The alley space is divided into a main alley shown at 20 occupying the major part of the width, and a starting alley 21 and extending substantially parallel thereto and located at one side thereof. The alleys are separated by a partition 22 which extends from the starting position toward the remote end, leaving sufficient space in the starting alley to provide for free throw of the ball through the latter space, the ball being represented on its proper scale at 23.

The pin space in the main alley is located adjacent the starting end or players position so that it is accessible for the player himself. As shown the space may be marked with suitable indexing spots 25 showing the positions for the pins. Immediately to the rear of the pin space the table is formed with a pit 26 into which the balls and the pins may fall when they are hit. The space is closed by an upstanding wall 27 so that the balls and pins are properly retained in this pit and thus immediately accessible to the player for resetting.

25 Means are provided at the remote end of the alleys for turning and deflecting the ball in a substantially horizontal plane so that when thrown up the starting alley it returns in the main alley in a direction toward the pins. This means embodies a construction of guide for receiving the ball as it comes from the starting alley and gradually and progressively deflecting the same in a horizontal plane, ultimately reversing its direction and causing its return toward the pins. This construction comprises a plurality of spaced strips 30 which are of variable length, and which stand lengthwise against the remote end of the alley and forward ends projecting forward by variable amounts. On the upper surface of the

30 numbers 30 there is positioned the initial or fixed guide element shown at 32. This element is formed with an arcuately curved guide face 33, the shape of the face being such as to provide initially a very slight curvature with the curvature progressively increasing so that the ball is gradually and progressively turned in direction as it passes thereover. The guide portion 32 may be conveniently supported on the strips 33 by means of nailing or glueing the same thereto.

45 The guide also incorporates a final or movable portion 35. This portion is of less arcuate length than the fixed portion, but has a shorter radius of curvature to provide for imparting a substantially equal deflection to the ball. It will be clear from Fig. 5 that the fixed guide 32 provides for

imparting a deflection to the ball of the order of 90°, while the remaining portion of the guide imparts the additional deflection to the ball, representing approximately the same or an even greater angular deflection.

Movable guide portion 35 is hingedly connected to the fixed guide portion 32 by means of hinge 37 fastened to the adjacent ends of the two guides, the hinge pin being preferably recessed below the outer surface of the guides so that it will not objectionably obstruct the passage of the ball. At its opposite end, movable guide portion 35 is supported by a strip 38 which carries a pair of spaced contact members 39 thereon which are adapted to slide over the surface of the 15 alley. Suitable elements for this purpose are metal glides of the chair leg type.

The movable guide element 35 is arranged to be resiliently supported so as to be variably deflected in response to the energy with which it is 20 engaged by the ball. For this purpose a tension spring 40 is fastened to the rear of the guide 35 adjacent the hinge 37, the other end being fastened to a fixed part of the frame. A stop 41 is provided on the frame for limiting the forward 25 travel of the guide under the action of the spring. It will be seen that with the structure thus described, the entire guide structure including the fixed and movable parts is raised above the level of the alley and is so located that its center is 30 substantially opposite the center of the ball.

In order to provide a smooth continuous covering against which the ball may engage, a strip of fabric is secured to the end of the movable guide as shown at 45, the fabric extending across the hinge connection, over the fixed guide and along the adjacent side of the starting alley, being preferably looped over the outer end of the frame and fastened to the outside as shown at 46. This forms a smooth and continuous engaging surface 40 for the ball wherever it may strike the wall of the alley or guide members.

In order to prevent the possible escape of the ball over the top of the alley, a top cover member 50 is provided at the remote end of the alley, such cover being shaped in general conformity with the shape of the guide members. It is positioned above the level of the guide members as shown in Fig. 4, and above the normal level of the balls when they are on the floor of the alley. It preferably overhangs the guide members a short distance as indicated in dotted lines in Fig. 1, the overhang 51 assuring against the ball jumping out of the alley regardless of the force with which it is thrown.

In the playing of the game the player manually throws the ball into the starting alley with a free throw since the alley is substantially wider than the diameter of the ball. The ball then engages the guide at a point depending upon the direction in which it is initially thrown, and continuing around the fixed guide portion engages the movable guide portion. There it effects a variable deflection of the movable guide portion depending upon the force which it has at that time, and is accordingly deflected in a variable direction back toward the pin position to engage the pins. Because of the variable factor thus introduced, the game has substantial interest and provides for considerable development of individual skill in determining the proper angle and force of throw of the balls in order to secure the best results in knocking over the pins.

While the form of apparatus herein described constitutes a preferred embodiment of the inven-

tion, it is to be understood that the invention is not limited to this precise form of apparatus, and that changes may be made therein without departing from the scope of the invention which is defined in the appended claims.

5 What is claimed is:

1. A bowling game of the character described comprising a main alley for receiving the bowling pins at one end thereof, a starting alley substantially parallel to and located at one side of said main alley, said starting alley having a starting position at the same end as that which receives the bowling pins, means to separate said alleys at the starting end thereof, curved horizontally extended guide means at the remote end of said alleys for receiving the bowling ball from said starting alley and deflecting the same in a horizontal plane and returning the same to said main alley, said guide means having an initial fixed portion and final movable portion, hinge means for adjustably connecting adjacent ends of said fixed and movable guide portions, a supporting member for said movable guide portion resting upon the floor of said alley and movable thereover with reduced frictional contact for supporting the free end of said member in spaced relation above the floor of said alley, and resilient means for yieldably urging said movable portion forwardly against the force of said ball and providing for variable displacement thereof about said hinge means dependent upon the energy of motion of the ball.

2. A bowling game of the character described comprising a main alley adapted to receive the bowling pins at one end thereof, a starting alley substantially parallel to and located at one side of said main alley and having a starting position at the same end as that which receives said bowling pins, means to separate said alleys at the starting end thereof, a curved horizontally extended guide member at the remote end of said alley for receiving the ball from said starting alley and deflecting and returning the same to said main alley to strike the pins, said guide member having an initial fixed portion and a final portion movable in response to contact of the ball, a hinge connection between said portions of the guide member, resilient means for yieldably holding said movable portion against the action of said ball providing for variable movement thereof to variably deflect said ball dependent upon the energy of motion thereof, and a flexible surface covering material extending continuously over said fixed and movable guide portions and 45 across said hinge connection forming a smooth and continuous engaging surface for contact with said ball.

3. A bowling game of the character described comprising a main alley adapted to receive the 60 bowling pins at one end thereof, a starting alley substantially parallel to and located at one side of said main alley and having a starting position at the same end as that which receives said bowling pins, means to separate said alleys at the starting 65 end thereof, a curved horizontally extended guide member at the remote end of said alley for receiving the ball from said starting alley and deflecting and returning the same to said main alley to strike the pins, said guide member having an initial fixed portion and a final portion movable 70 in response to contact of the ball, resilient means for yieldably holding said movable portion against the action of said ball providing for variable movement thereof to variably deflect said ball dependent upon the energy of motion thereof, and 75

a flexible surface covering material of fabric extending continuously over said fixed and movable guide portions and adapted to contact said ball.

4. A bowling game of the character described comprising a main alley adapted to receive the bowling pins at one end thereof, a starting alley substantially parallel to and located at one side of said main alley and having a starting position at the same end as that which receives said bowling pins, means to separate said alleys at the starting end thereof, a curved horizontally extended guide member at the remote end of said alley for receiving the ball from said starting alley and deflecting and returning the same to said main alley to strike the pins, said guide member having an initial fixed portion and a final portion movable in response to contact of the ball, resilient means for yieldably holding said movable portion against the action of said ball providing for variable movement thereof to variably deflect said ball dependent upon the energy of motion thereof, and means for supporting said both portions of said guide member above the level of said alleys leaving a substantial clearance therebetween and in position substantially opposite the center of said ball. 25

5. A bowling game of the character described comprising a main alley adapted to receive the bowling pins at one end thereof, a starting alley substantially parallel to and located at one side of said main alley and having a starting position at the same end as that which receives said bowling pins, means to separate said alleys at the starting end thereof, a curved horizontally extended guide member at the remote end of said alley for receiving the ball from said starting alley and deflecting and returning the same to said main alley to strike the pins, said guide member having an initial fixed portion and a final portion movable in response to contact of the ball, 10 resilient means for yieldably holding said movable portion against the action of said ball providing for variable movement thereof to variably deflect said ball dependent upon the energy of motion thereof, and an overlying covering member spaced above said guide members and projecting forwardly thereof with a limited overhang to normally be clear of contact with the ball throughout its engagement with said guide. 15
